Primary Examiner — Shawn T Gingrich*Assistant Examiner* — Bryan N. Melvin(57) **CLAIM**

The ornamental design for a generator cover, as shown and described.

DESCRIPTION

FIG. 1 is a top perspective view of a generator cover, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of FIG. 1, shown in the first state of use;

FIG. 10 is a perspective view thereof, shown in the second state of use; and,

FIG. 11 is a perspective view thereof, shown in the third state of use.

The broken lines in the drawings illustrate the portions of the generator cover, which form no part of the claimed design.
